UNITED STATES PATENT OFFICE.

THOMAS E. BROWN, OF NEW YORK, N. Y.; FLORENCE E. BROWN ADMINISTRATRIX OF
SAID THOMAS E. BROWN, DECEASED.

DRAWBRIDGE.

Application filed March 1, 1823. Serial No. 622,053.

This invention relates to that type of bascule bridge which has long been known as the "draw bridge", and which consists essentially of a pivoted movable span with 5 balancing beams pivotally supported above the bridge and connected at their outer ends to the movable span by tensional connections, balance being effected by heavy weights attached to the inner ends of said 10 beams.

In my copending application, Serial No. 557,442, filed April 29th, 1922, I show and describe a single leaf bridge, and this invention refers more particularly to double 15 leaf bridges of similar type.

The principal object of my invention is to suspend each movable leaf as a cantilever by means of the connections from the leaf to the balance beams which usually serve as 20 balancing connections only, and enable said connections to sustain not only the dead weight of the leaf but to sustain also the live load carried on the leaf, and this I do by aid of the weight of the counterweight 25 itself, and am enabled thereby to dispense with the folding hangers, hooks from beam to span and other devices heretofore used, and so greatly simplify the structure.

Another object of my invention is to neutralize the heavy horizontal trunnion thrust, 30 due to the combined live and dead loads on the leaf, by intersecting the main tower members at the level of the trunnion or pivot of the leaf, whereby moments from the 35 trunnion thrust are avoided and the usual auxiliary members required to resist such moments may be omitted, and also the resultant of the vertical forces at the channel pier is moved back from the trunnion and 40 therefore the channel pier may be set back from under the trunnion, enabling shorter leaves to be used in proportion to the required clear channel width, and especially 45 so when deep and massive foundations are required.

The means of accomplishing these as well as other objects of my invention will be understood from the description and the drawings.

50 Referring to the drawings:

Fig. 1 is a side view of one half of a double leaf bridge of my invention.

Figs. 1^a and 1^b are sectional views of a detail.

Fig. 2 is an end view at larger scale of 55 a portion of Fig. 1.

Figs. 3 and 3^a show modifications of the arrangement shown in Fig. 2.

Fig. 4 is a side view at a larger scale of 60 a portion of Fig. 1.

Fig. 4^a is a plan view of Fig. 4.

Fig. 5 is an end view, in partial section, of Fig. 4.

Fig. 6 is a side view of a special form of 65 trunnion.

Fig. 7 is an end view of Fig. 6, and

Fig. 8 shows my invention as applied to a bridge having long approach spans.

Similar characters refer to similar parts 70 in all the figures.

Referring more especially to Fig. 1, in which it will be understood that only the left hand end of the structure is shown and that the structure is repeated on the right hand end, the broken line Z—Z representing 75 the centre line of the river channel; A is a movable leaf of a bascule bridge, and B a fixed or tower span. 1 is a truss of said leaf A and 2 the trunnion or pivot about which it rotates. 4 and 5 are piers supporting the 80 bridge. The fixed span B comprises the member 7 and posts 8 and 9 and base 3. Said base 3 carries the trunnion 2 of the movable leaf A, and said posts 8 and 9 carry the pivot 10 of the balance beam 11, and 85 form with said member 7 a tower or counter-weight carrying frame.

6 is an additional post which supports the forward end of beam 11, when leaf A is in its lowered position, by means of seat 19 90 and bearing 20, said seat 19 being fixed on post 6, and said bearing 20 forming part of beam 11 and moving with it. Post 6 is held in position by brace 21.

On the inner or shore end of the balance 95 beam 11 and carried by said beam is the counterweight 12, and at the other end of said beam 11 is a pivot 13 to which is connected the short link 14 which in turn is connected by pivot 15 to the long link 16, 100 said long link 16 being connected to the truss 1 by the pivot 17, said short link 14 together with long link 16 forming a connection or hanger for truss 1.

18 is a stop, suitably placed on beam 11, to arrest the rotation of link 14 about pivot 13. Thus rotation of the links 14 and 15, during the first portion of the movement of the span 1, takes place about pivot 13 and so continues until said link 14 contacts with stop 18, after which rotation of link 16 takes place about pivot 15, and the positions of said pivots 13 and 15 and stop 18 are such that the counterweight substantially balances the movable leaf A in all its positions.

The inclined posts 6 and 9 terminate at their lower ends at substantially the same level as the trunnion 2, said post 6 being located sufficiently far back of the trunnion 2 to permit of full opening of the leaf A without interference of truss 1 with post 6, the said post 6 and post 9 being preferably in line with truss 1, i. e., all having the same plane of symmetry as shown in Fig. 4.

Dotted lines show the movable span in its fully open position, and also the counterweight in its corresponding lower position. It will be understood that in general the description refers to one side of the bridge only and that the parts described will usually be duplicated on the other side of the bridge.

The required location of pivots 13 and 15 and stop 18, to cause the counterweight to balance the movable leaf in all its positions, may be determined by the method described in my copending application hereinbefore referred to.

The bridge may be operated in any suitable manner, as by rack 22 and pinion 23 and by any suitable motor and mechanism adapted to rotate said pinion 23, also any of the usual forms of shear locks may be used if desired to lock the toe ends of the trusses 1 together where they meet at the centre of the channel Z—Z.

It will be seen by reference to Fig. 1, that with my construction the angular motion of the beam and its counterweight is not equal to the angular motion of the leaf and hence when the span is in its vertical position the counterweight 12 remains outside of the counterweight supporting frame—and I am enabled therefore to place the counterweight 12, beam 11, posts 6, 8 and 9, and seat 19 all in the same plane and hence said bearing 20 contacts with seat 19 and beam 11 is supported by post 6, hanger 16 thus supporting leaf 1 as a cantilever, when said leaf is in its lowered position as shown in Fig. 1, and by choosing a suitable position for the beam trunnion 10 said seat 19 may be placed so far forward of said beam trunnion 10 and so close to the hanger 16 that the moment of the counterweight about said seat 19 when the leaf is in its lowered position is greatly in excess of the moment about seat 19 of the combined live and dead

loads carried by the hangers 16 so both the live and dead loads of the leaf are sustained by said hanger and the leaf is positively supported under said loads by means of the weight of the counterweight itself, and the folding or detachable members usually used 70 are no longer required.

While my construction admits of, and I prefer placing the beam 11, post 6, and seat 19, all in the same plane, as shown in the partial end view Fig. 2—I do not confine myself to this construction, for as shown in Fig. 3, when for any reason the beam 11^b and the counterweight supporting frame together with post 6^b are not in the same plane I may use a cross girder 24^b and place seat 19^b on said cross girder 24^b as shown in Fig. 3. When as shown in Fig. 3^a beam 11^a is outside of post 6^a, seat 19^a may be placed on an extension of girder 24^a.

In draw bridges it is advantageous to place the trunnion 2 of the movable leaf 1 at or preferably slightly above the floor level as thereby serious complications at the heel floor break are avoided, and thus the trunnion 2 (see Fig. 1) is usually at a considerable height above the bridge pier 4. See also Figs. 4 and 5.

In double leaf bridges of the kind described the trunnion thrust is great and is substantially horizontal, the vertical components of said thrust, if any, being but a small proportion of the horizontal components. I therefore prefer to place the apex "a" of the tower members 6, 7 and 9, i. e. the point of intersection of the centre lines of said members, at the level of the trunnion 2, as thereby moments from the horizontal trunnion forces are avoided, and the vertical resultant of the forces in said members which constitutes the load on the bridge pier 4 coincides with the apex "a", therefore said pier 4 may be placed under said apex "a" instead of under trunnion 2, thereby enabling fender 25 to be placed further from the centre of the channel thus widening the channel of a double leaf bridge by an amount equal to twice the distance between the apex "a" and the trunnion 2, for, as will be clearly seen from Fig. 1, were pier 4 placed under trunnion 2—then fender 25 would be pushed out 115 and encroach on the channel and this encroachment would occur on both sides of the channel. Conversely, therefore (with an established channel width) my construction permits of the leaves being made shorter than in the usual construction in which the pier is under the trunnion. This results in an important economy in both weight of counterweight and weight of structure.

Referring again to Figs. 4 and 5—the base 3 is preferably formed of plates, (commonly known as gusset plates), and I provide short members 26 and 27 to act as stiffeners for

said gusset plates, and, if preferred, stiffening angles 28 may be used on the edges of said plates.

In bridges of large size carrying very heavy loads it may sometimes be desirable to avoid carrying the live load thrust through the trunnion. In such cases (see Figs. 6 and 7) I prefer to use a separate or live load bearing 29 below the trunnion, and support the bearings 32 of trunnion 2 on a pin 30 thus pivotally supporting trunnion 2, so said trunnion is slightly movable, as thereby ambiguity of stress from deflection of the movable span under the live load is avoided.

Referring to Fig. 8—my construction is specially applicable when, instead of short tower approaches, the approach spans B are long. In such cases, I prefer to so arrange the counterweight 12 and balance beam 11 that they may remain always above the approach span during the motion of the moving leaf A and I may place the seat 19 on the inclined end post 6 of the long approach spans B. In such cases the method of determining suitable arrangement of hanger 16 and its connecting links to effect a proper balance of the moving leaf will be understood from my copending application hereinbefore referred to and other patents cited therein.

A very light bridge may possibly be subjected to a live load heavier than the weight of the counterweight will sustain. In light bridges I prefer to use a stop 31^c, as shown in Fig. 8, said stop adapted to contact with and hold down the rearward end of beam 11^c should the live load on the movable leaf be sufficient to overcome the counterbalance weight and tend to lift the beam trunnion 10^c out of its bearings, and in the form shown in Fig. 1, in which the tower members end under pivot 10, I accomplish a similar result by extending the tower gusset plates above and over pivot 10 forming a stop 31.

Now, having described my invention, what I claim is:

1. A drawbridge comprising a movable leaf, a balance beam carrying a counterweight, a stop for the beam and a single connection adapted to transmit the weight of the leaf to the beam and adapted also to support the leaf in its lowered position from the beam.

2. A drawbridge comprising a movable leaf, a balance beam carrying a counterweight, a connecting member between said leaf and said beam and means for supporting the beam between its pivot and the point of attachment of said connecting member when the leaf is in its lowered position.

3. In a drawbridge comprising a movable leaf, a balance beam carrying a counterweight, a frame supporting said beam and a connection between said beam and said leaf,

a seat on said frame adapted to contact with and positively support said beam when said leaf is in its lowered position.

4. In a drawbridge comprising a fixed part a movable leaf, a balance beam carrying a counterweight and a connection between said beam and said leaf, a stop on said fixed part adapted to prevent further movement of said beam whereby said leaf, when in its lowered position, is positively supported by said connection.

5. In a drawbridge, the combination of a movable leaf, a balance beam carrying a counterweight, a frame supporting said beam, a connection between said beam and said leaf, and a seat on said frame adapted to contact with said beam and prevent further movement of said beam when said leaf is in its lowered position.

6. In a drawbridge, a movable leaf, a balance beam, a counterweight on the rearward end of said beam, a frame carrying the pivot of said beam, a connection between said beam and said leaf, said frame extended forward of said pivot and adapted to contact with said beam when said leaf is in its lowered position and prevent further downward movement of said leaf.

7. In a drawbridge, a movable leaf, a balance beam carrying a counterweight and a connection between said beam and said leaf and a fixed part having a plurality of points of support for said beam, one of said points of support arranged to cause the counterweight to sustain the live load on said leaf.

8. In a drawbridge, a movable truss having a pivot at its heel, a fixed counterweight supporting frame having an inclined post adjacent to said pivot, said post and said truss lying in the same vertical plane, said inclined post and co-acting members of said frame having their apex behind said pivot and substantially distinct from and at the level of said pivot, a base connecting said members and said pivot, a pier supporting said base and said pier centrally placed under said apex.

9. In a drawbridge, comprising a movable leaf having trusses at each side thereof, a support for said movable leaf having trusses at each side thereof, the trusses of said movable leaf and the trusses of said support being in the same vertical plane, trunnions movably connecting the trusses of said leaf and the trusses of said support, a pier adjacent to said trunnions adapted to carry the trusses of said support, the apex of the end members of the trusses of said support being back of and at a substantial distance from said trunnion, the center of said pier being vertically under said apex.

10. In a drawbridge, a movable leaf, a balance beam carrying a counterweight, a frame supporting said beam, a connection between said beam and said leaf, a seat on

said frame adapted to contact with said beam when said leaf is in its lowered position and a stop to prevent undue upward movement of said counterweight should overloading of said leaf lift said counterweight.

11. A drawbridge comprising a movable

leaf, a movable structure carrying a counterweight, a stop for said structure and a single connection adapted to transmit the weight of the leaf to said structure and adapted also to support the leaf in its lowered position from said structure.

THOMAS E. BROWN.
